ENVELOPE STRUCTURE FOR ELECTRON TUBES

Howard D. Deolittle, Stamford, Conn., assignor to
 Machlett Laboratories, Incorporated, Spring-
 dale, Conn., a corporation of Connecticut

Application December 4, 1950, Serial No. 199,075

4 Claims. (Cl. 313—308)

1

This invention relates to means for adjusting interelectrode spacing in electron tubes of coaxial construction and in particular concerns adjustment means in an envelope wall having a diameter in the order of, or greater than, one-half inch.

In the prior art, folds or convolutions in metallic envelope walls have been used successfully as interelectrode adjustment means. As opposed to an arrangement employing an inwardly extending fold formed in a reentrant portion of the tube envelope, I have used a radially outward extending fold formed in the exposed surface of the tube envelope. This construction has proved more accessible and more controllable than the inward extending fold. By axial compression of my convolution, an actual shortening of the axial length of the tube envelope takes place. Since elements in a vacuum tube are normally rigidly supported on the envelope wall, a decrease in wall length between the supports of two electrodes will cause corresponding decrease in interelectrode spacing of those elements. To date, such means have been employed to accurately obtain closer spacing between grid and cathode, hence higher transconductance, in inverted lighthouse tubes.

As higher frequency operation is sought, more precise control of the grid-anode spacing assumes importance. It is desirable to control this spacing within small limits in order to obtain uniformity in U. H. F. capacitance from tube to tube. Without such uniformity, substitution of one tube for another in any given cavity requires excessive retuning of the cavity to regain the desired resonant circuit. For instance, when used in an amplifier operating at a specific frequency, any change in the capacitance of the tube will require compensation by modifying the circuit constants of the cavity (changing its size) in order that resonance be returned to the desired frequency. Since a major change in tube capacity requires a major cavity adjustment, it is desirable to keep the change in capacity, hence the shift in frequency, as small as possible so that a minimum of retuning will be necessary. If a fold in the tube envelope could be used to obtain precise interelectrode spacing, the readjustment necessary in the cavity circuit would be very minor. But most grid to anode spacing folds would have to be placed on the anode terminal, and it has been shown in the past that folds formed in the envelope in general cannot stand atmospheric pressure if they are about one-half inch or more in diameter, as they would probably have to be in this case.

2

The factors most influential in the success of folds as adjustment means are the deformability of the metal used (which takes into account the gauge of the metal used) and the area of the fold exposed to atmospheric pressure parallel to the tube axis. Since deformability is a physical property of the metal it is a difficult parameter to change. This is because the kinds of metal possible for use in vacuum tubes, particularly for sealing to the envelope insulation, are limited. Likewise, it is unlikely that the gauge could be increased sufficiently to adequately decrease deformability since rather standard gauge material is used in electron tubes and heavier material would be cumbersome to form for small tube parts. The area of the fold exposed to axial atmospheric pressure, of course, is dependent upon the envelope diameter at its location.

My invention offers a simple solution to the problem of collapse of large folds. My invention consists of a relatively large fold formed directly in the metal tubing which constitutes a portion of the envelope and within that convolution a ring capable of plastic deformation. Use of some soft metal such as copper for this ring will prevent collapse of the convolution except under sufficient axial pressure of vice-like jaws to compress and deform the ring. When deformed the desired amount, the ring will still offer resistance to any further compression due to atmospheric pressure.

For a better understanding of my invention reference is made to the following drawing in which the figure shows a typical high frequency coaxial tube in axial section.

Referring to the figure the tube shown in axial section has within the vacuum envelope three planar active elements, a cathode 10 and grid 11 and an anode surface 12. The cathode 10 is indirectly heated by a heater element which is surrounded by tubular heat shield 14 attached at one end to the active cathode. The cathode itself is supported by a foil tube 15 which is in turn attached to a tubular member 16 forming an inner ply of the cathode terminal. This is sealed near the tube's end to the outer ply of the cathode terminal which is formed by tubular member 17. This terminal also acts as one of the heater terminals and is connected to the heater through lead 18. Axial lead 19 connects the other side of heater to cup terminal 20 which is within and coaxial with tubular members 16 and 17. An envelope portion affixed to the cathode terminal is composed of a metallic sleeve 21 sealed to insulating ring 22, which is in turn sealed to axial lead 19. A tubular insulator 23 is

also attached to insure separation of the heater terminals.

The grid 11 is held by support 24 which is rigidly connected by means of tubular member 25 and vitreous insulator 26 to cathode terminal 17. Thus, it may be seen that between the active cathode 10 and grid 11 there is a continuous rigid path formed by the support and terminal members. I have found it convenient to place a small outwardly extending radial fold 17a in the surface of tubular terminal member 17. Since the cathode terminal outer and inner tubular members 16 and 17 are sealed together near the end of the tube and above the radial fold, axial compression of this fold 17a will cause a decrease in the inter-electrode spacing between cathode and grid by virtue of the fact that this compression represents a shortening of the axial length of envelope between these two elements.

In similar fashion there is a rigid path between grid 11 and the active anode surface 12. The first step in this path is again grid support 24 which is affixed to tubular grid terminal 27. Vitreous ring insulator 29 is sealed to terminal 27 and insulates it from tubular anode terminal 30, which is sealed to the opposite end of ring 29. Anode terminal 30 may be sealed directly to the anode block 31 or indirectly thereto through reentrant shell member 32. Atop the anode block 31 is the active anode surface 12, and through the block is exhaust duct 34, terminated in seal-off tubulation 35.

Somewhere in the anode terminal surface 30 an outwardly extending radial fold 37 similar to fold 17a is formed. Because of its relatively large diameter this fold unsupported is unable to withstand atmospheric pressure. Therefore, I have introduced within the fold a plastically deformable ring 38. When vice-like jaws on opposite sides of the fold surrounding the tube are axially closed upon the fold 37 the ring 38 is permanently deformed. Thus, in compressing the radial fold 37 the axial envelope length between the grid and anode is decreased by virtue of the rigidity of the members forming a path between the grid 11 and anode surface 12. The ring when compressed will not return to its original shape, but will retain its new shape and thus support the radial fold 37 against collapse.

While the large radial fold described is especially valuable for the grid and interelectrode capacitance adjustment, radial folds of this kind are not restricted to this specific use or location. In fact, they may be employed in any envelope

location between any pair of electrode members where axial interelectrode spacing adjustment is desired and where an unsupported radial fold would be unable to withstand atmospheric pressure, or various forms of mechanical shock encountered in the course of using the tube.

I claim:

1. An electron discharge device having an anode and a cathode within a vacuum envelope, said envelope consisting in part of a tubular metallic member having an outwardly extending radial fold the inner surface of which is in continuous communication with the vacuum envelope and a ring of permanently deformable material usable within a vacuum envelope within said fold tending to prevent the collapse thereof under atmospheric pressure or mechanical shock.

2. An electron discharge device having an anode and a cathode within a vacuum envelope, the envelope portion between the anode and its adjacent electrode consisting in part of a tubular metallic member having an outwardly extending radial fold, and a ring of readily deformable metal within said fold tending to prevent the collapse thereof under atmospheric pressure or mechanical shock.

3. An electron discharge device having an anode, a cathode and a grid within a vacuum envelope, the envelope segment between anode and grid consisting in part of a tubular metallic member having an outwardly extending radial fold, and a ring of readily deformable metal within said fold tending to prevent the collapse thereof under atmospheric pressure or mechanical shock.

4. An electron discharge device having an anode, a cathode and a grid within a vacuum envelope, the envelope segment between any two active elements consisting in part of a tubular metallic member having an outwardly extending radial fold, and a ring of readily deformable metal within said fold tending to prevent the collapse thereof under atmospheric pressure or mechanical shock.
